ATTORNEY

UNITED STATES PATENT OFFICE.

JACOB KREISBERG, OF NEW YORK, N. Y.

HAIR CURLER.

Application filed February 16, 1927. Serial No. 183,484.

This invention relates to devices for curling and waving hair and particularly to the curler or curling "stick" upon which the hair is wound.

In using curling sticks of this type, a clip is usually used for clamping a strand of hair at a point near the scalp, after which the free end of the strand is wound upon the middle portion of said stick. As the strand is wound up, it occupies more of the length of the stick gradually spreading from the middle of the stick towards the ends, for the reason that while the free ends of the strand of hair may be compressed into a small area, the hairs of the strand diverge over a much greater area as the scalp is approached. If the stick is made of one piece as has been heretofore customary, the hairs which arrange themselves near the ends of the stick are not wound tightly enough with consequent loss of efficiency in the curling or waving operation. I have therefore provided a stick wherein the ends are rotatable relatively to the middle portion and to each other in a direction effective to wind up the strand thereon tightly.

The various objects of my invention will be clear from the description which follows and from the drawings, in which,

Fig. 1 is a front view of my improved curling stick showing how the winding of the strand thereon is begun.

Fig. 2 is a vertical central section of my device.

Fig. 3 is a section of a modification.

Fig. 4 is an end view of the same, and

Fig. 5 is an end view of the same partly in section showing particularly the means for preventing backward rotation of the ends.

In the illustrated embodiment of my invention which shows one of the practical applications thereof, I provide a central portion 10 preferably of the same length as or somewhat longer than the separate end sections 11 of the stick. At its middle, the

diameter of the section 10 is least, the diameter of said section increasing gradually towards the ends thereof in a suitable curve so that the shape of said section is substantially a hyperboloid of revolution or other suitably shaped concave cylindrical solid.

Through the center of the section 10, is the coaxially arranged longitudinal, cylindrical opening as 12 through which a supporting rod as 13 may be passed in such a manner as to properly support said section, which may

be suitably secured to the rod as by means of a pin 14. It will be understood however, that the section 10 may be made of sheet material if desired, and similarly or otherwise secured to the rod, or that said rod and said section 10 may all be made of a single piece of material if desired. Annular shoulders as 15 are provided at the ends of the section 10, said shoulders being of the proper depth to allow the ends 16 of the end sections 11 to fit thereinto in such a manner that the entire outer surfaces of the sections 10 and 11 are perfectly flush or even with each other with no space therebetween in which hairs may be caught. In other words the joint is tight and smooth to prevent possible catching of or injury to the hair or pain to the person whose hair is being treated. The extensions 17 at the extremities of the section 10 fit inside of the ends 16 and provide a bearing for supporting said ends 16 during the rotation thereof.

I prefer to have the outer extremities 18 of the end sections 11 greater in diameter than the inner ends 16 thereof the cross-sectional diameter of said sections increasing gradually to provide a curved surface continuous with the surface of section 10. A base as 19 preferably closes the outer circular end of each of the sections 11 and has a central aperture 20 therein to allow the passage therethrough of the rod 13, said base being made preferably though not necessarily integral with the remainder of said end section.

For maintaining all three of the sections of the stick in place, the extremities 21 of the rod 13 are suitably threaded to engage the nuts 22, which are adapted to be tightened on said rod against the bases 19, whereby the parts are maintained coaxially in proper longitudinal and transverse relation, though said parts may be relatively rotated or readily detached for repair, cleaning or the like, as will be clear from Fig. 2.

For preventing rotation of the sections 11 in the wrong direction, that is, in a direction tending to loosen the strand of hair wound thereon, a ratchet wheel as 23 is secured to the rod 13 as by means of a suitable pin 24, ratchet teeth as 25 inclined in the proper direction being cut on the face of said wheel. For engaging the teeth 25, a spring projection 26 may be cut from the base 19 as by means of the parallel curved slits 27 and 28 and the radial slit 29 joining

said slits, the material between said slits being then bent inwardly so as to lie preferably in a plane substantially parallel to the axis of the rod 13, or a separate spring member may be used for this purpose if preferred. The projection 26 is made of sufficient length to engage the teeth 25 and to prevent backward rotation of the section 11. It will be understood however, that any suitable clutch arrangement allowing rotation in one direction only may be substituted for the ratchet and the ratchet engaging means shown.

In the operation of my improved stick, a strand of hair 30 of suitable size at the scalp to cover the greater part of the stick when wound up, is arranged substantially about the middle of the section 10 and the stick is turned toward the scalp in the usual manner thereby winding up the strand upon said section. Since the free ends of the hair occupy a substantially less width than that occupied by the root ends of the hair, as the stick is rotated, the strand tends to spread longitudinally upon the stick, gradually reaching and being wound upon the sections 11. Because of the divergence of the outer hairs of the strand 30, said hairs are not wound ordinarily, tightly upon the sections 11, if said sections are rotated together as a unit or given the same number of revolutions as the section 10. It therefore becomes advisable to rotate the sections 11 forwardly toward the scalp independently of and relatively to the section 10 to complete the winding operation. This is readily done in my improved device by slightly tensioning the strand 30 so that the hair already wound on the section 10 cannot loosen up, and then rotating the end sections 11 toward the scalp, said sections being gripped at the ends 18 thereof.

In order to provide means whereby the end sections 11 may be rotated with considerable force as is sometimes necessary when the hair is wound tightly thereon, I prefer to provide suitable projections 35 projecting longitudinally from the ends thereof. Said projections may be formed if desired, from the material of the bases 19 by means of suitable slits as 36 in somewhat the same manner as the projections 26 are formed. For bracing the projections 35 and for allowing the insertion of a suitable rod, a pin as 37 may be riveted to said projections 35 as clearly shown in Figs. 3 and 4. By means of this construction pliers or other tools may be inserted between the projections 35 in order to exert greater force thereon than would be ordinarily possible with the fingers alone. Suitable knurling 31 is provided at said ends 18 so that the fingers may obtain a firm hold upon said ends. It will be noted that the sections 11 cannot rotate backwardly being held in place by means of the

projection 26 which engages the teeth 25.

It will be seen that I have provided an efficient curling stick in which all of the hairs of a strand may be tightly wound, which is simple in construction and efficient in operation. Various changes from the preferred structure shown are contemplated, and I do not therefore intend to limit myself to the specific construction illustrated, but intend to avail myself of the equivalents afforded by the range of the appended claims.

I claim:

1. In a hair curling stick, a middle section adapted to have the ends of a strand of hair wound thereabout, and to receive the middle hairs of the strand on the rotation of said section, and a pair of end sections, each adapted to have the outside hairs of the strand wound thereon and each mounted coaxially with, and for rotation relatively to said middle section.

2. In a hair curling stick having a smooth, continuous, concave cylindrical surface, an intermediate section of less than the full length of said stick and adapted to have hair wound thereon, outer sections rotatable relatively to said middle section in one direction only, and adapted to receive the outer hairs of a strand and means for detachably securing said sections together.

3. In a hair curling stick, a middle section serving as a part of said stick, a pair of end sections of greater diameter forming the remainder of said stick, the outer surface of said sections being concave and the cross sections thereof being circular, means for allowing relative rotation of said sections in one direction only, and means for detachably securing said sections together for rotation as a unit.

4. In a hair curling stick, adapted to have a strand of hair wound thereon in concentric turns one outside the other and having a smooth, continuous concave, cylindrical surface, a middle section, a pair of end sections each engaging one end of said middle section and supported thereby, means passing through said sections for removably maintaining said sections in longitudinal coaxial alignment, and means for allowing relative rotation of said sections in one direction only and for allowing rotation of all said sections as a unit.

5. A three piece curling stick comprising a pair of similar end sections, and an intermediate section of substantially the same length as and between the said end sections, mounted for independent rotation in one direction only relatively to said end sections, the cross sections of said stick at various points being circles of different diameters, least at the middle and increasing toward the ends, whereby a strand of hair may be wound principally upon the intermediate

- section in concentric overlaying turns and the edge hairs of the strand may be separately tightened upon the end sections, while maintaining the tight winding of the strand 5 on the intermediate section.
6. A curling stick comprising inter-engaging sections arranged in longitudinal coaxial alignment and having a concave cylindrical, smooth surface, means arranged 10 coaxially in and passing through said stick for maintaining the sections in place and means on the outside of the ends of said stick for removably securing the parts together.
15. 7. A curling stick comprising three sections arranged in longitudinal coaxial alignment and having a concave cylindrical, smooth, outside surface, a rod arranged coaxially in and passing through said stick, 20 means on said rod engaging the outside of the ends of said stick for removably securing the parts together, and means for allowing relative rotation of the end sections and the middle section in one direction only.
25. 8. In a curling stick, a middle section having a concave, cylindrical surface, a constricted, cylindrical projection at each end of said section having a shoulder thereon, and a pair of end sections mounted in said 30 stick for rotation relatively to said middle section and each adapted to have one end abut against one of said shoulders, said end being of the same thickness as the depth of said shoulders for providing a smooth outer 35 surface at the joint between said middle section and said end sections.
9. A curling stick comprising a middle section, end sections of substantially the same length as said middle section, joints 40 forming a smooth continuous outside surface between said sections, means for allowing independent rotation of each of said end sections in one direction only, and extensions near the ends of said end sections whereby 45 said end sections may be forcibly rotated.
10. A curling stick comprising three separate sections arranged in longitudinal coaxial alignment and having a smooth concave, cylindrical outer surface, a depression in 50 each of the ends of the middle section adapted to receive and support a corresponding end of the end section, means for detachably securing the sections together, means for allowing relative rotation of said sections, and projections on the end sections 55 adapted to have force applied thereto for rotating said end sections.
11. In a three piece curling stick, independently rotatable end sections, and braced
- projections on said end sections adapted to 60 be turned forcibly for rotating said sections.
12. In a curling stick, bases closing the ends thereof, a pair of projections outstanding substantially at right angles to and formed from the material of each of said 65 bases, and a pin extending between and bracing each pair of projections.
13. In a curling stick, three independently rotatable sections of substantially the 70 same length arranged to provide a continuous smooth outside surface on said stick, and means for detachably securing said sections together.
14. In a three piece curling stick, a middle section, an end section of substantially 75 the same length as said middle section mounted on and supported by each end of said middle section and providing a smooth continuous outside surface on said stick, bases substantially closing the end of each of 80 said end sections, projections extending from each of said bases whereon force may be applied for rotating each of said end sections independently of each other and of said middle section, and means for detachably 85 securing all of said sections together.
15. A hair curling stick comprising a middle section of circular cross section throughout, of least outside diameter at the middle 90 thereof, and of greatest outside diameter near the ends thereof, a continuous outwardly concave surface on said section, radially arranged, inwardly extending shoulders near the ends of said section, said section having a central longitudinal opening therethrough, 95 a pair of similar end sections adapted to abut against the shoulders of said middle section, a perforated base integral with and closing the extremity of each of said end sections, an outwardly concave surface on 100 each of said end sections, the outside diameter of said surface at one end thereof being the same as the greatest diameter of said middle section for providing a continuous smooth outer surface on said curling stick, 105 and the diameter of each of said end sections being greatest near the base thereof, a rod passing through the opening in said middle section and the perforations of said end sections, means at the ends of said rod for engaging said bases and detachably securing 110 said sections together, and means connected to said rod and said end sections for allowing rotation of said end sections relatively to said middle section and to each other in a 115 given direction only.

JACOB KREISBERG.
